UNITED STATES PATENT OFFICE.

WILLIAM H. HUTCHINSON, OF ROCHESTER, NEW YORK.

DESIGN FOR A BURIAL-CASKET KNOB.

SPECIFICATION forming part of Design No. 15,014, dated May 27, 1884.

Application filed November 12, 1883. Term of patent 7 years.

To all whom it may concern:

Be it known that I, WILLIAM H. HUTCHINSON, of Rochester, Monroe county, New York, have invented or produced a new and original

5 Design for Molds of Burial-Casket Knobs; and I do hereby declare that the following is a full, clear, and exact description of the same, reference being had to the accompanying drawings, in which—

10 Figure 1 is an elevation of the device. Fig. 2 is a plan of the same.

This design relates to burial-casket knobs; and it consists of a knob with a circular body, provided with convex ornamental projections 15 on its sides, as hereinafter more fully described.

In the drawings, A shows the knob. The head or portion which forms the finger-hold is circular in outline. On its sides are any desired number of radial projections or nipples,

a a, the outer edges of which are convex vertically. The faces *b b* of the knob between the projections are rounding, as shown, following the circle of the knob.

This design presents a highly ornamental 25 appearance, as the projections break the smooth outline of the knob, and it adds much to the attractive appearance of the knob.

Having described my production, I claim—

The design consisting of a knob having a 30 circular head and radial projections thereon convex vertically, as herein shown and described.

In testimony whereof I have hereunto signed my name in the presence of two subscribing 35 witnesses.

WILLIAM H. HUTCHINSON.

Witnesses:

R. F. OSGOOD,

P. A. COSTICH.
